UNITED STATES PATENT OFFICE

CHARLES F. REINMANN, OF PITTSBURG, PENNSYLVANIA, ASSIGNOR TO THE
WESTINGHOUSE ELECTRIC COMPANY, OF SAME PLACE.

METHOD OF TESTING ELECTRIC-LAMP GLOBES.

SPECIFICATION forming part of Letters Patent No. 374,850, dated December 13, 1887.

Application filed October 1, 1887. Serial No. 251,187. (No model.)

To all whom it may concern:

Be it known that I, CHARLES F. REINMANN, a citizen of the United States, residing at Pittsburgh, in the county of Allegheny, in the State 5 of Pennsylvania, have invented certain new and useful Improvements in the Method of Testing Electric-Lamp Globes, of which the following is a specification.

The invention relates to a method of preparing incandescent-electric-lamp globes for the purpose of exhausting the air therefrom.

The object of the invention is to provide a convenient method for determining whether or not the lamps are hermetically sealed to the 15 fork or tube through which they are exhausted.

The invention consists in placing the lamp-bulbs and the fork, to which they are temporarily sealed, in a tank of water or other liquid and connecting the fork with a source 20 of gas or air under pressure. If there is a leak at any of the joints or in any of the globes, the air or gas will escape therethrough and rise to the surface of the water in the form of bubbles, thus indicating that there is a leakage and the point at which it takes place.

In the accompanying drawing there is shown a set of lamps placed in a tank for carrying out the operation.

Referring to the drawing, A represents a 30 tank containing water or other fluid, as indicated at B. The lamp-globes D D are sealed to the fingers c c of the fork C. This fork consists of a central tube, c', from which the tubes c radiate. The tubes c open into the tubes d

at the ends of the lamp-globes in a manner 35 well understood. The central tube is connected by a rubber tube or in any other convenient manner with a gas-pipe, E, or any other suitable supply of gas or compressed air. After the fork is thus connected the stop-cock 40 e may be opened and the fork and the attached lamps placed beneath the surface of the water. In case there is an imperfect joint or an opening in any of the globes or the necks of the same it will become evident by the gas passing 45 through and escaping to the surface of the water.

It is evident that this process may be carried out without in any manner injuring the filaments of the lamps or permitting the water 50 to enter the globes.

I claim as my invention—

The hereinbefore described process of testing lamp-globes previous to their exhaustion, which consists in placing them, after they 55 are attached to their supporting-forks, beneath the surface of a liquid, and in forcing air or gas under pressure into the same and noting whether or not the air or gas escapes through the liquid.

In testimony whereof I have hereunto subscribed my name this 15th day of September, A. D. 1887.

CHARLES F. REINMANN.
